(57) **CLAIM**

The ornamental design for an aircraft sideledge, as shown and described.

DESCRIPTION

FIG. 1 is a perspective view of the aircraft sideledge showing our new design;

FIG. 2 is a front view of the aircraft sideledge of FIG. 1; FIG. 3 is a left view of the aircraft sideledge of FIG. 1; FIG. 4 is a right view of the aircraft sideledge of FIG. 1; FIG. 5 is a top view of the aircraft sideledge of FIG. 1; and, FIG. 6 is an enlargement of a portion of the top view of the aircraft sideledge as indicated in FIG. 5.

The evenly spaced broken lines in the drawings depict portions of the aircraft sideledge that form no part of the claimed design. The dot-dash broken lines in the drawings depict the bounds of the claimed design and form no part thereof. The dot-dash broken line circle in FIG. 5 shows an area for annotating enlargements in FIG. 6 and forms no part of the claimed design.
